MAKING INSULATED WIRE

Aaron Rosenstein, New York, and Harry Dolan, Brooklyn, N. Y., assignors to Rosenstein Bros., New York, N. Y., a firm composed of Aaron Rosenstein, Charles Rosenstein, and Irving J. Fuller, partners

Application September 10, 1942, Serial No. 457,842

1 Claim. (Cl. 154—2.26)

1

This invention relates to insulated wire and a method of manufacturing the same.

Insulated wire consists usually of a copper core which is enclosed in a rubber tube and a textile sheath. Present day methods involving a separate manufacture of the textile and rubber coverings are expensive and consume a great deal of time.

Our copending application pertaining to "Making covered threads," filed September 10, 1942, Ser. No. 457,843, Patent No. 2,355,471, dated August 8, 1944, describes the manufacture of a covered thread by continuously wrapping an artificial thread, as it is being extruded, around a core which may consist of an elastic thread.

An object of the present invention is to adapt the method described in said patent application to the manufacture of insulated wire.

Another object is the provision of a simple, inexpensive and effective method of manufacturing insulated wire.

A further object is the provision of insulated wire having a permanent, firm and durable covering, sheathing or coating.

Other objects of the present invention will become apparent in the course of the following specification.

The objects of the present invention may be realized by utilizing freshly extruded non-elastic and elastic threads as coverings for the insulated wire, the freshly extruded non-elastic thread being continuously wound upon or wrapped around an elastic wrapping of the wire, or vice versa. The elastic and non-elastic coatings may be applied to the wire in a continuous operation.

The invention will appear more clearly from the following detailed description when taken in connection with the accompanying drawing showing, by way of example, a preferred embodiment of the inventive idea.

In the drawing:

Figure 1 is a diagram illustrating a method of manufacturing insulated wire.

Figure 2 is a diagram illustrating a somewhat different method.

Figure 3 shows diagrammatically an insulated wire.

Figure 1 of the drawing illustrates a conducting wire 5 which may consist of a single core or of a plurality of braided or interwoven wire elements made of copper, aluminum or the like.

The wire 5 is covered in the course of one step of the process by a covering 6 consisting of a freshly extruded rubber compound or other suitable plastic insulating material, such as gutta

2

percha or a solution of furfural, cellulose acetate and phenolic resin. The elastic thread 6 may be extruded through an opening 7 of a bottom portion or spinneret 8 constituting a part of a tank 9. The tank 9 is immovable and receives its solution 10 through a pipe 11.

The bottom portion 8 of the tank is rotated in the direction of an arrow 13 by a pulley 12 driven by an endless belt 14. The rotary portion or element 8 is carried by a sleeve 15 and is separated from a flange 16 of the immovable tank 9 by a packing 17. The sleeve 15 is carried by the flange 16.

A tube 18 is integral with the rotary bottom 15 8 and extends through the top 19 of the immovable tank 9.

As the wire 5 is drawn through the tube 18, the bottom portion 8 is rotated to wind the elastic thread 6 which is extruded through the opening 7, upon the wire 5.

The wire 5 carrying the thread 6 is passed through a heated tube 26 thereby baking the thread 6. Then the wire is drawn through another tube 180 carried by a rotary spinneret 80 which is suspended from a tank 90. The spinneret 80 is rotated in the direction of an arrow 20 by a pulley 120 driven by an endless belt 140. The spinneret 80 has an extrusion opening 70.

A so-called "soup" or artificial-thread solution 30 22 is introduced into the tank 90 and spinneret 80 through a pipe 110. An artificial thread 21 which is freshly extruded through the opening 70 is wound upon the windings of the insulating thread 6.

Then the wire 5 carrying an insulating winding 6 and windings of an artificial thread 21 is passed through an impregnating or waterproofing solution 22 situated in a container 23. The wire passes over a pulley 24 and is drawn in the direction of an arrow 25.

Figure 2 illustrates the coating of a wire 5 by a layer 27 of an insulating material 28. The wire passes through a tapered core tube 29 carrying an electric heater 34 and situated in a container 45 30 having an extrusion opening 31 and filled with the plastic insulated material 28. A piston 33 movable within the cylinder or container 30 is used to compress the plastic material 28 at the time when it is applied to the wire 5. Thus a 50 thin concentric coating 27 is applied under pressure to the wire 5 as it passes through the opening 31.

The coated wire is passed through a heater 26 and then a freshly extruded artificial thread 21 55 is wound upon it. The thread 21 emerges out

of the rotary spinneret 80 while the coated wire passes through the tube 180 extending through the tank 90 and the spinneret 80. The windings of the artificial thread 21 may be impregnated or otherwise treated in the usual manner.

It is apparent that the invention shown above has been given by way of illustration and not by way of limitation and that the methods and articles described above are subject to wide variation and modification without departing from the scope or intent of the present invention. All of such variations and modifications are to be included within the scope of the present invention.

For instance, the wire 5 may be provided with

a coating 21 of artificial non-elastic thread in a first operation, and then the layer 6 of rubber may be wound upon the coating 21.

What is claimed is:

5 The method of manufacturing insulated wire which comprises, in combination, continuously extruding an insulating material and winding it upon a conducting metal core, baking the insulating winding, continuously extruding a non-elastic artificial thread and winding it upon the insulating layer, and then water proofing the artificial thread covering.
